FOLDING TENT

Eugene A. Benka, 1835 W. Rogers St., Milwaukee, Wis., and Lawrence E. Kotek, Milwaukee, Wis. (13045 W. Van Norman Ave., New Berlin, Wis.)

Filed Oct. 2, 1959, Ser. No. 843,996

5 Claims. (Cl. 135—1)

The present invention generally relates to a tent structure and more particularly to a portable and foldable tent.

The primary object of the present invention is to provide a foldable and collapsible tent which renders the tent portable and will provide adequate protection from rain, sun, insects and may provide cover and protection around a picnic table and generally may be employed for any use for which a tent is adapted.

Another object of the present invention is to provide a portable and foldable tent which will collapse into an extremely small compact unit for ease of portability and which incorporates several novel features for facilitating ease of setting up and collapsing and providing a sturdy dependable tent structure.

A further object of the present invention is to provide a folding tent which is simple in construction, easy to fold, easy to unfold, light weight, sturdy in construction, adapted for many uses and generally inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the tent of the present invention;

FIGURE 2 is a perspective view of the tent frame with the tent cover removed with portions thereof broken away for clarity;

FIGURE 3 is a perspective view of the tent frame in collapsed condition;

FIGURE 4 is a detailed sectional view through one side portion of the tent illustrating the relationship of the tent cover and frame;

FIGURE 5 is a detailed plan view of the juncture between the top member of the tent frame and one of the side rails;

FIGURE 6 is a side elevational view of the construction of FIGURE 5;

FIGURE 7 is an end view of the construction of FIGURE 5;

FIGURE 8 is a detailed sectional view of one of the legs illustrating the structure of the lock mechanism for the telescopic legs;

FIGURE 9 is a detailed sectional view taken substantially upon a plane passing along section line 9—9 of FIGURE 8 illustrating further structural details of the leg lock;

FIGURE 10 is a detailed sectional view through the connection between the leg members and the side rails;

FIGURE 11 is a detailed sectional view through one of the leg members at the lower end thereof illustrating the construction thereof;

FIGURE 12 is a sectional view illustrating the manner of attaching the tent cover to the tent frame; and

FIGURE 13 is a detailed sectional view of the connection between the leg and braces.

Referring now specifically to the drawings, the numeral 10 generally designates the tent of the present invention which includes a tent cover generally designated by the numeral 12 and a tent frame generally designated by the

2

numeral 14 and which is illustrated in detail in FIGURE 2.

The tent frame includes a generally rectangular frame member designated by the numeral 16, a transverse generally inverted U-shaped center frame member designated by the numeral 18 and corner legs generally designated by the numeral 20. The rectangular frame 16 includes sectional side rails 22 and the sections of the side rails 22 are hingedly interconnected and connected to the ends of the center frame member 18 by a bracket generally designated by the numeral 24. The outer ends of the sectional side rails 22 extend inwardly towards each other in sections 26 and are telescopically engaged with a central section 28 which cooperate with the sections 26 to form end rails of the frame 16. The center frame member 18 includes end sections 30 and a central section 32 telescopically received in the facing ends of the sections 30. The outer ends of the outer sections 30 extend downwardly in substantially L-shaped configuration as designated by the numeral 34 for connection to the brackets 24.

Each corner of the frame 16 is provided with an anchor eye bolt 36 to which is connected a chain 38 which extends to and is connected to the center of the central section 32 of the top cross frame 18 which connection may be by virtue of an eye bolt 40 or the like.

Adjacent each end of the side rail 22, there is provided a sleeve 42 to which the adjacent cooperating corner leg 20 is pivoted. Each corner leg 20 includes an upper section 44 and a plurality of telescopic lower sections 46 and 48 with the lowermost section 48 having a cap or foot 50 thereon constructed of resilient material or the like for engaging a supporting surface. The upper end of the upper section 44 is provided with a sleeve 52 secured thereto by anchor members such as rivets 54 (FIG. 10) with the diametrically opposed upper end portions of the sleeve 52 extending upwardly in slightly diverging relation as flanges or ears designated by the numeral 56 which have inwardly projecting indentations or projections 58 therein which engage with corresponding indentations 60 and 62 in the sleeve 42 and side rail member 22 which not only provides a latching effect for the corner legs but also locks the sleeve 42 longitudinally on the rail member 22. The forward edges of the sleeve-straddling flanges 56 are positively and pivotally connected to the sleeve 42 by a hinge pin 64 or the like which may also serve to anchor the sleeve 42 in its intended position. Thus, the spring flanges 56 and the indentations 58 therein serve to form a snap lock for the legs 20 for retaining the legs 20 in extended relation with the legs at each end extending downwardly in diverging relation to the legs at the other ends as illustrated in FIGURE 2.

FIGURES 8 and 9 illustrate the structure for locking the lower leg section in longitudinally adjusted position which structure includes a slot 66 in the upper end portion of the lowermost section 48 and a plug 68 disposed interiorly of the tubular lower section 48 at the upper end thereof with the plug 68 having a cam surface 70 facing the slot 66 for rollingly engaging a cam roller 72 which may have a knurled outer surface and which is disposed in captive relationship in the slot 66 as far as longitudinal movement thereof is concerned. The periphery of the roller 72 may be knurled for engaging the inner surface of the next upper section 46 of the leg whereby relative rotation between the sections 48 and 46 will cause the roller 72 to selectively lock the section 48 in adjusted relationship to the section 46, thereby enabling longitudinal adjustment of the sections of the legs and locking of the longitudinal adjustment in a secure manner at any point desired.

The lower end of the lowermost section 48 which has

the cap 50 thereon may also be filled or partially filled with concrete 76 (FIG. 11) for adding weight to the bottom portion of the tent frame. Also, an eye bolt 78 extends through the cap 50 and the lower end of the lower section 48 and serves to retain the cap 50 in position which may also rely upon friction or any other means for securing the cap in position. The bolt 78 is provided with a laterally extending eye 80 for receiving a pointed ground inserted stake 82 which has an eye 84 on the upper end thereof and which is inserted into the ground surface 86 for anchoring the legs 20 in position.

The legs 20 are interconnected by brace member generally designated by the numeral 88 which includes telescopic outer and inner sections 90 and 92 with the outer section being rotatably connected with the legs 20 by connection means 93 (FIG. 13).

FIGURES 5-7 illustrate the details of the bracket structure 24 for connecting the sections of the side rails 22 to the outer sections 30 of the top rail or frame 18. The elbow-type down-turned ends 34 of the sections 30 are actually independent of the sections 30 and connected thereto by fastening members 94. The lower ends of the depending members 34 are received in socket-forming tubular sleeves 96 having an elongated pin 98 extending through the lower end thereof and extending outwardly of the sleeve 96.

Attached to each section of the sectional side rail 22 is a substantially U-shaped bracket 100 and 102 which clips under the sections of the rail 22 on either side of the line of juncture between the sections. The inner end of each U-shaped member 102 is provided with an upwardly and longitudinally extending pivot lug or ear 104 which are in transverse alignment with each other and through which the elongated hinge pin or fastener 98 extends thus hingedly interconnecting the sections of the side rail 22, hingedly interconnecting the U-shaped brackets 102 and 100 and hingedly attaching the brackets 100 and 102 and the sections of the side rails 22 to the sleeve 96.

Rigidly affixed to the bracket 100 is an arcuate plate 106 secured by a fastening rivet 108 which also secures the bracket 100 to the section of the side rail. The U-shaped bracket 102 is also provided with an arcuate plate 110 secured to the section of the rail and to the bracket 102 by a fastener 112 similar to fastener 108. The upper and inner edges of the plates 106 and 110 overlap as illustrated in FIGURES 5 and 6 when the sections of the side rail 22 are in horizontal alignment with these ends of the plates 106 and 110 having an aperture 114 therein for receiving the end of a spring loaded pin 116 which is provided with an eye 118 on the inner end thereof which is disposed inwardly of the sleeve 96 whereby the pin 116 may be retracted from engagement with the aligned apertures 114. A coil spring 120 is disposed within the sleeve 96 and has one end engaging the inner surface of the sleeve 96 and the other end engaging an abutment 122 on the pin 116 thus urging the free end of the pin 116 into engagement with the apertures 114. When the pin 114 is retracted, the sections of the rail 22 cannot move downwardly about pivot pin 98 due to the abutting ends of the brackets 100 and 102. However, upward movement of the sections of the side rails 22 may be accomplished and the plates 106 and 110 will further overlap each other and pass downwardly in relation to the rails 22 whereby additional apertures 124 are provided in each plate 106 and 110 which are aligned with the pin 116 when the sections of the side rail 22 are disposed in alignment and adjacent relation as illustrated when the tent frame is collapsed as shown in FIGURE 3.

Thus, the spring pin 116 will lock the frame 16 in extended position as illustrated in FIGURE 2 and will permit collapsing thereof and folding thereof for subsequent locking in a folded condition.

The cover 12 includes a top member 126 having a depending skirt portion 128 which receives the frame 16.

The top 126 includes a ridge portion 129 and a relatively small gable end portion 130 for conforming to the top cross frame 18 with the gable 130 providing vertical height to the top 126. The top 126 is connected to the frame 16 by a plurality of loop members 132 (FIG. 12) in the form of straps which have one end thereof anchored to the cover by virtue of stitching 134 and having the other end detachably connected thereto as by snap fastener assembly 136 thereby wrapping around the side rail 22 and detachably connecting the cover 126 to the frame 16 with the flanges 128 depending on the outer surface thereof and concealing the various structural features of the framework and especially the frame 16.

Depending from the frame 16 are curtain-like side panels 138 which are formed of panels that may be detachably connected to form an entrance opening 140 in a conventional manner. The upper ends of the panels 138 are connected to and drape the side and end rails of the frame 16 by virtue of releasable suspension hooks 142 which extend through grommets 144 in the upper ends of the panels 138. The hook shaped members 142 slidably engage the frame 16 and are somewhat in the nature of a means for supporting a shower curtain from a shower rod. The panels 138 are preferably constructed of a screen mesh material designated by the numeral 146 with the lower edge of the material 146 being weighted as at 148 and engaging the ground surface for conforming the lower edge of the cover to the ground surface and preventing entry of insects or the like.

The canopy or top is preferably constructed of a light weight waterproof and sunproof material such as canvas or the like. The concrete in the legs serve as weights for preventing shifting of the legs and the cross tubing is adjustable and will act as a drying rack for articles such as bathing trunks, towels or the like. All of the telescopic elements of the frame may be locked in adjusted position with a lock such as the leg lock as illustrated in FIG. 8. Referring now specifically to FIGURES 8 and 13 of the drawings, the connection 93 between the brace 30 and the leg 20 includes a reduced area or portion 150 on the leg section 46 which is outwardly flared at the lower end as indicated by numeral 152. This structure relatively captures a split sleeve 154 which has spaced lugs 156 projecting from one side thereof. Mounted on the outer end of the brace section 90 is a cap 158 retained in position by a transverse pin 160. The cap 158 is provided with a longitudinally extending lug 162 received between the legs 156 and pivotally connected thereto by a transverse pin or rivet 164.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A portable folding framework for a space enclosing covering embodying a protective weatherproof canopy and cooperable curtain walls comprising: a horizontal rectangular top frame embodying a pair of duplicate coplanar companion half-sections each U-shaped in plan and embodying spaced limbs joined at corresponding outward ends by a bight portion, said bight portion being extensible and contractible and permitting said limbs to be adjusted toward and from each other, the inward ends of the limbs of the half-sections being joined together by hinges having horizontal axes, an extensible and retractable inverted U-shaped canopy elevating member having the function of a crosswise ridge pole and transversely spanning the space between and in a plane above the plane of the limbs of the respective half-sections, said ridge pole member having its downwardly directed arms pivoted to the respective hinges, and at least one arm being provided

with a spring-loaded latch pin releasably engageable with keeper holes provided therefor on the adjacent hinge, and supporting legs, one for each corner of said frame, said legs being foldable against the half-sections when said half-sections have been collapsed and folded together with said ridge pole member therebetween, said legs being extensible and contractible and having their upper ends permanently hinged to their respective corner portions, none of the parts of the overall framework being detachable and the framework, thus unified, being easy to erect and collapse with no parts capable of being lost or misplaced.

2. The structure according to claim 1, and in combination, horizontal cross-braces interposed between each companion pair of legs, said cross-braces embodying telescoping components, being extensible and contractible and permanently bracketed to their respectively intended legs.

3. The structure defined in claim 1, and wherein the lower end of each leg is weighted and provided with a foot-forming cap held in place by an eye-bolt piercing the cap and leg, the accessible eye of said eye-bolt adapted to accommodately hold a ground anchoring spike.

4. The structure according to claim 1 and wherein the inner ends of the legs at the locale of said adjacent hinge are provided with a pair of upstanding segmental flat rigidly attached plates which are overlapped and provided with alignable selectively usable keeper holes for said latch pin.

5. A portable folding framework for a tent-forming

covering comprising a horizontal frame embodying adjustable U-shaped half-sections having limbs whose inner adjacent ends are hingedly joined, leg attaching sleeves encircling and fixed on the respective limbs adjacent the corners of the frame, foldable frame supporting legs for the corner portions of the frame, said legs being made up of telescoping upper, lower and intermediate sections, the upper section of each leg having a fixed connecting sleeve thereon below and at an angle to the cooperating attaching sleeve on the adjacent limb, said connecting sleeve having upstanding ears straddling and pivoted on the attaching sleeve, both sleeves having coacting detents, the lower section being internally weighted and having a fixed hold-down eye available for an anchoring spike, the lower and intermediate sections being tubular and having a self-contained rotary friction lock for adjusting and retaining the sections in a set relationship.
